P. VAN VLissingEN

PRINTING DEVICE

Filed July 28, 1923

UNITED STATES PATENT OFFICE.

PETER VAN VLASSINGEN, OF CHICAGO, ILLINOIS, ASSIGNOR TO SYCO SYSTEMS COMPANY, OF CHICAGO, ILLINOIS, A CORPORATION OF ILLINOIS.

PRINTING DEVICE.

Application filed July 28, 1923. Serial No. 654,331.

To all whom it may concern:

Be it known that I, PETER VAN VLASSINGEN, a citizen of the United States, and a resident of Chicago, in the county of Cook and State of Illinois, have invented certain new and useful Improvements in Printing Devices, of which the following is a specification.

This invention relates to improvements in printing devices and more particularly to type holders or forms having changeable type, such as rubber hand stamps or the like.

The principal object of the invention is to provide a new and improved device of the character described in which the type may be readily set or removed. Further objects of invention will appear from time to time as the description proceeds.

My invention may best be understood by reference to the accompanying drawing, illustrating one form in which it may be embodied. In the drawing:

Figure 1 is a rear view in perspective of an assembled stamp constructed in accordance with my invention.

Figure 2 is a face view of the stamp shown in Figure 1.

Figure 3 is a view in perspective of a single type holder or unit forming part of the completed stamp.

Figure 4 is a transverse sectional view of the holder shown in Figure 3, but drawn to a larger scale.

Figure 5 is a view in perspective of a type setting stand used in connection with the holder unit shown in Figure 3.

Referring to details of the embodiment of my invention shown in the drawing, the printing device is made up of a plurality of separate type holding units 10, 10 each designed to receive and hold a single line of type 11, 11 therein. An individual holding unit is shown in Figure 3, with the type removed, and comprises a body portion having a relatively thick base portion 13 and a thinner upper portion 14, provided with a recessed central portion 15, along the upper edge forming the seat for the type. The holding pieces may be constructed of any suitable material, such as metal or wood. Flexible holding members 17, 17 extend along opposite sides of said central recess, to form a walled recess or groove within which the type is set. In the preferred form

shown, the holding members 17, 17 are comprised of a single rubber band 16 which may be of the ordinary form, extending over upright shoulders 18, 18 formed in slots 19, 19 at opposite ends of the unit, said band being deeper than the recess 15, and under sufficient elastic tension to be retained in place. A bed piece 20 of resilient material such as rubber may also be secured along the bottom of the recess 15. Any suitable means may be used for securing said bed piece, as for instance by gluing or cementing the same. The total width of the upper portion 14 and the two thicknesses 17, 17 of the rubber band is substantially the same as the width of the base portion 13, the arrangement being such that the outer surfaces of said rubber bands are substantially flush with adjacent sides of said base.

The holding units 10, 10 may be made in various widths, each accommodating a type of a different height, as clearly shown in Figure 2. The width of the upper portion 14 of the holder is by preference slightly less than the type used therein, so that when the type is in position between the bands, the latter will be extended slightly. Thus the type will be securely held under compression when several such holding units are clamped side by side to form a completed stamp, as will now be described.

The separate holding units 10, 10 are secured side by side in the desired order by suitable means, such as by assembling them on a transversely extending bar 22 having dove-tailed engagement with recesses 23, 23 in the base of said holding pieces. When finally assembled form, as shown in Figures 1 and 2, a pair of rigid end pieces 24, 24 are placed on opposite sides of the extreme outer units, and the whole clamped together by suitable means such as rods 26, 26 extending through apertures 27, 27 formed in the ends of the units 10, 10 and tightened by wingnuts 28, 28 or the like, threaded on said rods. A handle 30 may be carried on the transverse bar 22, by which the assembled stamp may be held when used as a hand stamp. It will be understood however, that the device is not limited to hand stamps, but may also be conveniently applied to any form of printing press, where hand-set type is used.

The flexible or elastic band 17 permits

the type to be set in the individual holders much quicker and easier than has heretofore been possible with type holders of the usual construction, yet when assembled as described the type is securely held against displacement by lateral engagement of adjacent units, or, in the case of the extreme outer units, by the rigid end pieces 24, 24. Forms having types of varying sizes can be used, and furthermore my device may be used with either metal or rubber type as desired. The rubber bands 17 are readily replaceable in case of injury or wear.

For convenience in setting type in the individual holders 10, 10, I also provide a setting stick 35 to be used in conjunction with my device. This stick comprises a base 36, having a longitudinally disposed groove 37 on the top thereof adapted to receive a holder unit 10 in loosely fitting engagement therein. The groove is sufficiently deep for the greater portion of its length so that the opposite marginal edges 38, 38 are substantially the same height as the top 25 of the rubber band 17, but an end portion of the stick is cut down so that marginal edges 39, 39 will be below the top edges of said band, as shown. The arrangement is such that the type may be readily inserted 30 in the holder at a point above the lower marginal edges 39, 39, because the rubber band 17 is free to spread laterally at this point, but as the setting of type proceeds, the completed portion is moved between the 35 higher marginal edges 38, 38, where the type is held securely until the setting is completed. The unit may then be assembled with similar units to make the completed stamp, as has already been described.

Although I have shown and described one specific form in which my invention may be embodied it will be understood that other arrangements and constructions may be used without departing from the scope 45 of my invention. Therefore, I do not wish to be understood as limiting myself to the construction illustrated, excepting in so far as specifically defined in the appended claims.

I claim as my invention:

1. In combination, a type holding member provided with a pair of parallel flexible tension members forming a groove for holding type under lateral pressure of said tension members, and a separable frame for receiving said holding member and providing lateral support for said flexible tension members to secure said type in place with a relatively greater degree of rigidity than that afforded by said flexible tension members.

2. A plurality of separable type holding members each provided with a pair of parallel flexible members forming a groove 65 for receiving type, and means securing said

holding members together with adjacent flexible members in mutual supporting engagement.

3. A plurality of separable type holding members each provided with a pair of parallel flexible members forming a groove for receiving type, means securing said holding members together with adjacent flexible members in mutual supporting engagement, and rigid supporting means for the extreme outer type holding members.

4. In combination, a frame, a separable type holding unit provided with a pair of parallel flexible tension members forming a groove for receiving and holding type and independent of said frame, said frame having means between which said holding unit may be secured, with said flexible members supported under lateral pressure.

5. In combination with a frame, a removable type holding member provided with a pair of parallel flexible tension members along opposite sides thereof and forming a groove for receiving type, said frame having laterally movable means between which said holding member may be secured, with said flexible members supported under lateral pressure.

6. In a device of the character described, a type holder comprising a member recessed along one edge and provided with flexible tension members supported on opposite sides of said recess to form a groove for receiving and holding type under longitudinal elastic tension of said flexible members.

7. In a device of the character described, a type holder comprising a member recessed along one edge and provided with flexible members consisting of an endless rubber band supported on opposite sides of said recess to form a groove for receiving type.

8. In a device of the character described, a plurality of separable type holders each comprising a member recessed along one edge and provided with flexible members supported on opposite sides of said recess to form a groove for receiving type, and means for securing said holders together with adjacent flexible members in mutual supporting engagement.

9. In a device of the character described, a plurality of separable type holders each comprising a member recessed along one edge and provided with flexible members supported on opposite sides of said recess to form a groove for receiving type, means for securing said holders together with adjacent flexible members in mutual supporting engagement comprising a pair of rigid end pieces, and a clamping device adjustably connecting said end pieces together.

10. In a device of the character described, a plurality of separable type holding units each comprising a member recessed along

one edge and provided with flexible tension members supported on opposite sides of said recess to form a groove for holding type independently of each other, means for securing 5 said holders together with adjacent flexible members in mutual supporting engagement, a pair of rigid end pieces, and a pair of clamping members passing through said holders and said end pieces.

11. In a device of the character described, 10 a plurality of separable type holders each comprising a member recessed along one edge and provided with flexible members supported on opposite sides of said recess to 15 form a groove for receiving type, a supporting member having dove-tailed engagement across the base of each of said holders and a handle on said supporting member.

12. In a device of the character described, 20 a type holder comprising a member recessed along one edge and provided with flexible tension members supported on opposite sides of said recess to form a groove for holding type under longitudinal elastic tension of 25 said flexible members, and a resilient bed member along the bottom of said recess.

13. In a device of the class described, a 30 type form made up of a plurality of separable units, each comprising a member having a recess along one edge, a pair of shoulders on opposite sides of said recess, an endless flexible band supported under tension on said shoulders and extending on opposite

sides of said recess to form a groove for holding type, and means securing said units 35 together.

14. In a device of the class described, the combination with a type holding unit comprising a grooved member provided with flexible type retaining walls, of a device for 40 holding said unit while setting type, comprising a slotted member for receiving the unit, having upper marginal edges along one portion thereof extending upwardly into position to limit lateral movement of said 45 flexible walls, and having other marginal edges cut away to permit relatively greater lateral movement of said flexible walls.

15. A type holder comprising a body member having end supports, and a continuous flexible member passing around said end supports to form a type receiving groove. 50

16. A type holder comprising a body member having end supports and a continuous flexible member passing around said 55 end supports and maintained under tension to form a type receiving groove.

17. A type holder comprising a member having end supports substantially defining the height of the type to be received thereby, 60 and a pair of spaced tension members extending between adjacent sides of said end supports to form a type receiving groove.

In witness whereof, I hereunto subscribe my name this 25th day of July, A. D., 1923.

PETER VAN VLissingen.
